UNITED STATES PATENT OFFICE.

REUBEN FORD, OF NEWTON, MASSACHUSETTS.

DESIGN FOR A PUZZLE-CARD.

SPECIFICATION forming part of Design No. 29,856, dated December 20, 1898.

Application filed October 15, 1898. Serial No. 693,668. Term of patent 3¹ years.

To all whom it may concern:

Be it known that I, REUBEN FORD, a citizen of the United States, residing at Newton, in the county of Middlesex and State of Massachusetts, have invented and produced a new and original Design for a Puzzle-Card, of which the following is a specification, reference being had to the accompanying drawings, forming part thereof.

10 Figure 1 is a plan, and Fig. 2 an elevation, of a puzzle-card, showing my new design.

As shown in the drawings, the leading or material feature of my design consists of a series of slots in a plate or sheet of circular

shape radiating from a central circular slot 15 that is not continuous and terminating at points within and equidistant from the periphery of said plate.

Having described my invention, what I claim as new, and desire to secure by Letters 20 Patent, is—

The design for a puzzle-card as herein shown and described.

REUBEN FORD.
